CONCRETE BLOCK MANUFACTURING
METHOD AND MACHINE

Floyd D. Hyde, El Cajon, Calif., assignor to Inventors Development Company, San Diego, Calif., a corporation of California

Application August 9, 1948, Serial No. 43,293

32 Claims. (Cl. 25—41)

My invention relates to a concrete block manufacturing machine, and the objects of my invention are:

First, to provide a machine of this class which initially vibrates material, removing substantially all of the compressible fluids therefrom, and then slugs said material with a hammer blow, completing the compaction of the material into a mold, whereby very strong and homogeneous concrete blocks are produced;

Second, to provide a concrete block manufacturing machine of this class which vibrates the material into a preformed structure preliminary to the compaction of the material into the mold by a hammer blow, which initially slugs the material and forces the same to the bottom of the mold, creating a secondary shock wave which passes throughout the entire column of the material in the mold, greatly improving the compaction of the structure following vibration thereof;

Third, to provide a machine of this class from which formed blocks are delivered singly at a high rate of speed, whereby thin, small pallets for supporting each block greatly reduce the overall material requirements in the supplying of pallets to receive the production of the machine;

Fourth, to provide a machine of this class which produces a large volume of concrete blocks, and delivers them singly on single pallets, whereby great production may be accomplished, and the blocks may be individually handled at the conveyer extending from my concrete block manufacturing machine, permitting the yard workers to individually remove the block laden pallets from the conveyor and stack them at opposite sides thereof.

Fifth, to provide a machine of this class which produces concrete blocks of extremely high compressive strength in proportion to the blocks delivered from conventional vibrator molds;

Sixth, to provide a concrete block manufacturing machine of this class which delivers very accurate and smooth surfaced blocks;

Seventh, to provide a concrete block manufacturing machine of this class which is very compact in proportion to the production thereof;

Eighth, to provide a concrete block manufacturing machine of this class having novel vibrator structure in connection with the material hopper thereof, which continually compacts material into preformed arrangement coinciding with the forming mold of the machine;

Ninth, to provide a machine of this class having a slugging ram which ultimately forms blocks by slugging and which is adjustable in weight for increased compaction of concrete blocks, as desired;

Tenth, to provide a concrete block manufacturing machine of this class having novel forming mold and transfer box structure, which conveniently delivers individual concrete blocks at a high rate of speed, whereby each block is delivered on an individual thin pallet for convenience in handling;

2

Eleventh, to provide a concrete block manufacturing machine of this class which effectively excludes air and other compressible fluids from the forming mold during the compaction of a preformed block therein; and

12 Twelfth, to provide a concrete block manufacturing machine of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a top or plan view of my concrete block manufacturing machine, showing portions thereof broken away to amplify the illustration; Fig. 2 is a side elevational view thereof, showing portions broken away and in section to amplify the illustration; Fig. 3 is an enlarged fragmentary end view of my concrete block manufacturing machine; Fig. 4 is a longitudinal sectional view thereof, taken from the line 4—4 of Fig. 3, showing parts and portions in elevation and fragmentarily; Fig. 5 is a fragmentary sectional view taken from the line 5—5 of Fig. 3, showing portions broken away to amplify the illustration; Fig. 6 is a fragmentary sectional view taken from the line 6—6 of Fig. 3; Fig. 7 is a reduced fragmentary sectional view taken from the line 7—7 of Fig. 3; Fig. 8 is a fragmentary plan sectional view taken from the line 8—8 of Fig. 4; Fig. 9 is a fragmentary plan sectional view taken from the line 9—9 of Fig. 5; Fig. 10 is a fragmentary sectional view taken from the line 10—10 of Fig. 5; and Fig. 11 is an enlarged fragmentary sectional view taken from the line 11—11 of Fig. 1.

Similar characters of reference refer to similar parts and portions throughout the several views of the drawings.

The frame 1, hopper 2, ram 3, preforming core 4, vibrator diaphragms 5 and 6, backing plates 7 and 8, arms 9 and 10, links 11 and 12, vibrator shaft 13, eccentric bearings 14, pulleys 15 and 16, belt 17, motor 18, brackets 19 and 20, mold box 21, transfer box 22, mold block ejector 23, transfer box block ejector 24, ejector elevator 25, links 26, bell crank 27, link 28, lever 29, cam follower 30, cam 31, ram elevating levers 32 and 33, links 34 and 35, ram elevating cams 36 and 37, cam shaft 38, fulcrum shaft 39, ram guides 40, 41, 42 and 43, mold supporting toggles 44 to 47, inclusive, toggle shaft 48, mold supporting shoes 49 and 50, toggle operating cam 51, link 52, lever 53, cam follower 54, spring 55, pivot shafts 56 and 57, shafts 58 and 59, mold box cam 60, link 61, lever 62, cam follower 63, pallet chute 64, pallet feed slide 65, transfer box elevator cams 66 and 67, cam followers 68, levers 69 and 70, links 71 and 72, block delivery cam 73, lever 74, cam follower 75, link 76, bell crank 77, slide plate 78, guide rollers 79 and 80, clips 81, guides 82 and 83, motor 84, gear box 85, sprockets 86 and 87, chain 88, pallet take-out rollers 89 and 90, shafts 91, 92 and 93, gears 94 to 98, inclusive, motor 99, material flow regulators 100 and 101, and the set screw 102 and 103 constitute the principal parts and portions of my concrete block manufacturing machine.

The frame 1 is provided with base beams 1a having legs 1b, extending vertically therefrom, on which the upper horizontal beams 1c are supported. Extending upwardly from these horizontal beams 1c are columns 1d and 1e, supporting the cam actuating structure of the ma-

chine, together with the cam shaft 38, all as shown best in Fig. 2 of the drawings. The hopper 2 is supported on the beams 1c of the frame 1, at opposite sides thereof, and this hopper 2, as shown in Fig. 4 of the drawings, is provided with a preforming mold structure 2a at its base, which is supported on opposite sides of the machine on the beams 1c. This performing mold structure 2a coincides with the cavity 21a of the mold box 21, as shown in Fig. 8 of the drawings, which is a plan view of the forming mold box. The upper end of the preforming mold structure 2a is provided with a ledge 2b, which forms an abutment for the material compacted in the hopper 2 by the vibrator diaphragms 5 and 6, which are downwardly converging, as shown best in Fig. 4 of the drawings. The vertical abutment 2b prevents wedging of the compacted concrete material against the ram 3 when it passes downwardly into the preforming mold structure 2a during the ramming of a preformed block into the coinciding cavity 21a of the mold box 21. This cavity 21a above the plate 23a serves as a forming mold. Internally of the preforming mold structure 2a of the hopper 2 is the preforming core 4, around which the ram 3 is positioned and vertically reciprocally mounted. This ram 31 is shaped to coincide with the cavity 21a of the mold box 21, shown best in Fig. 8 of the drawings. The ram 3 is supported on cross members 3a, which extend through slots 2c and 2d in opposite sides of the hopper 2, which are inwardly of the ram housing structure 2e, integral with opposite sides of the hopper 2. This ram housing structure 2e is enclosed at its upper end and terminates in spaced relation with the abutment edges 2b of the preforming mold structure 2a, and prevents the block making material from flowing into the area transversed by the ram 3. The material flow regulators 100 and 101 are vertically slideable plates adapted to be projected downwardly below the lower edges 2f of the ram housing 2e in order to regulate the flow of various mixes of material used in manufacturing concrete blocks. These flow regulators 100 and 101 act as gates to control the depth of material in the hopper below the ram. Opposite ends of these regulators 100 and 101, near their upper edges, 100a and 101a, respectively, project through opposite sides of the hopper 2 and are flanged, as shown in Fig. 2 of the drawings. The flange 101b of the material flow regulator 101, shown in detail in Fig. 2 of the drawings, is provided with a longitudinal vertically disposed slot 101c, through which the set screws 102 and 103 project for fixing this material flow regulator 101 in various vertically adjusted positions, as desired, whereby the lower edge thereof may be positioned at a certain location intermediate the lower edge 2f of the ram housing 2e, and the abutment ledge 2b of the preforming mold structure 2a. The vibrator diaphragms 5 and 6 are preferably made of flexible or resilient material, such as rubber or synthetic material, as desired, and fixed to the outer sides of these diaphragms 5 and 6 are the backing plates 7 and 8, which are preferably made of fairly rigid material, such as mild steel, or the like.

Spaced outwardly from these backing plates 7 and 8, the outer edges of the diaphragms 5 and 6 are fixed to the hopper 2, permitting each of the diaphragms 5 and 6 to flex intermediate its connection with the hopper 2 and the respective backing plates 7 and 8. These vibrating diaphragms 5 and 6, as shown in Fig. 4 of the drawings, are connected to the backing plates 7 and 8, respectively, near the outer edges of said backing plates by frames 7a and 8a, respectively, internally of the diaphragms 5 and 6, and these frames 7a and 8a are within the openings 2g and 2h in the inclined lower portions of the hopper 2 provided to accommodate the flexing vibrating diaphragms 5 and 6. Pivotedly connected to the arms 9 and 10 at their lower ends by the shafts 9a and 10a are the backing plates 7 and 8. These shafts 9a and 10a pass through clevis portions integral with the backing plates 7 and 8, and the upper ends of the levers 9 and

10 are pivotally connected to extending hopper supported clevis portions integral with the hopper 2 by means of the pins 9b and 10b, respectively. Rigidly mounted on the hopper 2 are the brackets 19 and 20, having the bearing blocks 19a and 20a secured thereto, in which the vibrator shaft 13 is revolvably mounted. Fixed on this shaft 13, at its opposite ends, are the eccentrics 14. The pulley 15 is fixed to an intermediate portion of the vibrator shaft 13 and engages the belt 17 passing over the pulley 16 on the shaft of the motor 18, all as shown best in Figs. 1 and 2 of the drawings. Eccentric bearings 14 engage eccentric portions of the shaft 13 and carry clevis members 19b and 20b through which the shaft 9a extends. The shaft 9a pivotally supports one end of each of the links 11 and 12, which are pivoted at their opposite ends on the shaft 10a. Thus, motion of the eccentrics of the shaft 13 is transmitted to the bearings 14 which transfer the motion equally to the shafts 9a and 10a, on which the arms 9 and 10 are pivotally mounted, and on which the clevis portions of the diaphragm backing plates 7 and 8 are mounted. The mold box 21, having the cavity 21a, hereinbefore described, therein, is slidably mounted longitudinally of the frame beams 1c on the rollers 21b, shown in Figs. 2, 8 and 10 of the drawings. The pallet slide 65 being connected to the mold box 21 moves in unison therewith. These rollers 21b, shown in Fig. 10 of the drawings, traverse tracks 21c, resting on the upper sides of the inner lower flanges of the beams 1c, which are conventional I-beam sections. This mold box 21 reserves as a forming mold and is provided with a screed plate portion 21g adapted to cover the lower portion of the preforming mold structure 2a when the forming mold 21 is out of index therewith. From the forming mold 21 to the screed plate 21g is the link 61 pivotally connected to the lever 62 by the pin 62a, all as shown best in Fig. 4 of the drawings. The upper end of the lever 62 is stationarily mounted on the pivot shaft 56 and pivoted to an intermediate portion of the lever 62 by means of the pin 63a is the cam follower 63, which engages an internal track 60a of the cam 60 fixed to the cam shaft 38, which is driven by the sprocket 87 engaging the chain 88 passing over the sprocket 86 on the extending shaft 85a of the gear box 85, driven by the motor 84, shown best in Fig. 2 of the drawings.

Reciprocally mounted in the cavity 21a of the mold box 21 is the vertically movable mold block ejector 23. This mold block ejector 23 is provided with a plate 23a, which operates as a bottom for the forming mold 21 and conforms in shape to the cavity 21a of the mold box 21, which is shown best in Fig. 8 of the drawings. The mold box 21 is provided with bars 23e and 23f, forming a fixed stop or abutment for the plate 23a; and being disposed in spaced relation to the lower end of the forming mold 2a. This plate 23a is supported on legs 23b, which are carried by the roller frames 23c, having rollers 23d resting on the tracks 25a of the ejector elevator 25. The clips 81 on the mold box 21 engage the roller frames 23c when the plate 23a is flush with the upper portion of the mold box 21 and the lower portion of the forming mold 2a. These tracks 25a are pivotally connected to the links 26 at their upper ends by means of pins 26a, shown best in Fig. 2 of the drawings. The lower ends of the links 26 are fixed to the shafts 58, while the bell crank 27, fixed to the shaft 59 at one end thereof, supports one end of one of the tracks 25a by means of the pin 27a. The link 28 is pivotally connected to the bell crank 27 by means of the pin 27b, and the opposite end of the link 28 is pivotally connected to the lever 29 by means of the pin 29a. The upper end of the lever 29, as shown in Fig. 5 of the drawings, is pivotally connected to the frame columns 1e by means of the pivot shaft 56, which also provides a pivotal bearing for the hereinbefore described lever 62, shown in Fig. 4 of the drawings. Intermediate its ends, the lever 29 is provided with a trunnion 29b on which the cam follower roller 30 is mounted, which engages the profile

surface of the cam 31, which is fixed on the cam shaft 38, hereinbefore described.

The mold supporting toggles 44 to 47, inclusive, are arranged to support the mold box 21 during the fall of the ram 3, protecting the rollers 21b from shock in connection with the track 21c, shown in Fig. 10 of the drawings. The toggle links 45 and 47 are connected to the shaft 48 and pivotally connected with these toggle links 45 and 47 are the toggle links 44 and 46, respectively, by pins 45a and 47a. The upper ends of the toggle links 44 and 46 are connected to the shoes 49 and 50 by the pins 44a and 46a, respectively. These shoes 49 and 50 engage the lower side of the mold box 21, as shown in Fig. 10 of the drawings, when the toggles 44 to 47, inclusive, are in the aligned position, as shown in Fig. 5 of the drawings. It will be noted that the toggle links 45 and 47, extend into the bearing blocks 48a and 48b, supporting the shaft 48 on the lowermost beam 1a of the frame 1 at opposite sides of the machine, shown best in Figs. 2, 5 and 10 of the drawings. The clevis portion 52a of the link 52 is pivoted to the pin 45a in connection with the toggle links 44 and 45. Engaging the closed end 52b of this clevis member 52a is the spring 52d, adjacent the head 52c at the end of the link 52, which provides for resilient action of the link 52 in connection with the toggle links 44 and 45, after they have reached vertical alignment, as shown in Fig. 5 of the drawings. The link 52, at its one end, is connected in pivotal relation with the lower end of the lever 53 by means of the pin 53a, and the upper end of the lever 53 is pivotally supported by the pivot shaft 57, connected to the upright 1d of the frame 1, shown in Fig. 2 of the drawings. The spring 55 tends to hold the lever 53 toward the cam 51, and the cam follower roller 54 is pivotally mounted on the trunnion 53b, projecting from the lever 53, and this cam follower roller 54 engages the profile surface of the cam 51 fixed on the cam shaft 38, hereinbefore described.

As hereinbefore described, in connection with Fig. 4 of the drawings, the bars 3a of the ram 3 extend outwardly through the slotted openings 2c and 2d in the sides of the hopper 2, and are connected to the ram guide bearings 3b, vertically reciprocally mounted on the guide rods 40 to 43, inclusive, shown in Figs. 1 and 2 of the drawings. Supported on the bearing members 3b are weights 3c, which may be varied, as desired, for loading the ram in proportion to the particular mix of material and the size blocks being formed within the mold box 21. Pivotally connected to the cross members 3d and 3e fixed to opposite ends of the bars 3a are the links 34 and 35, respectively. Pivotally connected to the lower ends of these links 34 and 35 are the levers 32 and 33, respectively, which operate as ram elevating levers in cooperation with the ram elevating cams 36 and 37. These ram elevating levers 32 and 33 are pivoted on the fulcrum shaft 39, supported in connection with the columns 1e of the frame 1 by stationary bearing blocks 39a and 39b, shown best in Figs. 1 and 2 of the drawings. Each of the cams 36 and 37 is provided with a radical precipice terminating at opposite ends of a spiral profile surface. The cam 36, shown in Fig. 2 of the drawings, engaged by the cam follower 36a, pivotally mounted on the trunnion 32a of the lever 32, is shown in position following the drop of the ram 3, occasioned by the passage of the roller 36a over the edge 36b of the cam precipice. These ram actuated cams 36 and 37 are secured in fixed relationship with the cam shaft 38 near opposite ends thereof, at opposite sides of the frame 1 of my concrete block manufacturing machine, as shown best in Fig. 1 of the drawings.

The transfer box 22, shown in Fig. 4 of the drawings, is provided with a cavity, 22a, therein, which conforms with the external shape of a block formed in the cavity 21a of the mold box 21, shown in Fig. 8 of the drawings. This transfer box 22 is open at its normally lower side, and positioned in the upper portion of the cavity 22a thereof, in substantially stationary position, is the plate

24a of the transfer box block ejector 24. This ejector 24 is vertically movable mounted in connection with the pallet chute 64, and is provided with a plurality of vertically reciprocally mounted shafts 24b, which are provided with collars 24c, engaging springs 24d, abutted to the upper cross members 24e, shown in Fig. 1 of the drawings, through which the plungers 24b reciprocate when moved upwardly, it being noted that each of the plunger shafts 24b is provided with an enlarged washer 24f, fixed to its upper end, bearing on the upper side of the cross members 24e, shown best in Fig. 1 of the drawings. These washers 24f suspend the plungers 24b and provide an abutment for the load of the springs 24d exerted downwardly on the washers 24c fixed to the plungers 24b, all as shown best in Figs. 1 and 4 of the drawings.

The links 71 and 72 are pivotally connected to the trunnions 22b and 22c at opposite ends of the transfer box 22, while the upper ends of these links 71 and 72 are pivotally connected to the extending ends of the levers 69 and 70, which are pivoted intermediate their ends on the fulcrum shaft 39, all as shown best in Figs. 1 and 2 of the drawings. As shown in Fig. 6 of the drawings, the lever 69 is provided with a pin 69a at its cam-engaging end, on which the roller cam follower 68 is revolvably mounted and adapted to coincide with the plane of the cam 66, and engage the profile surface thereof as it rotates about the axis of the cam shaft 38 on which it is fixed. The slide plate 78, shown in Fig. 1 of the drawings, is slideable intermediate the guide rollers 79 and 80 on the upper side of one of the beams 1c of the frame 1. The inner end of this slide plate 78 reciprocates on a common plane with pallets under the transfer box 22, directly above the lower leg 65a of the pallet feed slide 65. Fixed to the outer end of the slide plate 78 are trunnions 78a engaged by a longitudinal slotted portion 77a of the bell crank 77, which is pivoted intermediate its ends on a pin 77b, fixed to an extension 1f of the frame 1, shown best in Fig. 3 of the drawings. The inner end of the bell crank 77 is pivotally connected to the link 76 by the pin 76a, and the opposite end of the link 76 is pivoted by means of the pin 76b to the lever 74 at its lower end. The cam follower roller 75 is revolvably connected with the lever 74 intermediate its ends, and bears on the profile surface of the cam 73, fixed on the cam shaft 38, shown best in Fig. 7 of the drawings. The upper end of the lever 74 is pivotally mounted on the pivot shaft 57, shown best in Figs. 1 and 7 of the drawings.

The pallet take-out rollers 89 and 90, at their adjacent peripheral portions, are arranged to engage pallets ejected by the slide plate 78 and force them on to a conveyor for transporting individual blocks as delivered from my concrete block manufacturing machine. These pallet take-out rollers 89 and 90 are mounted on the shafts 93 and 91, respectively, having mitre gears 97 and 94 fixed thereon, which mesh with the mitre gears 98, 96 and 95, respectively. The gears 96 and 95 are fixed to an intermediate synchronizing shaft 92, while the gear 98 is fixed to the shaft of the motor 99, which operates the pallet take-out rollers 89 and 90 continuously during operation of my concrete block manufacturing machine. It will be here noted that the cam shaft 38 is supported in pillow block bearings 38a, on cross members 1g fixed intermediate the frame columns 1d and 1e, shown in Fig. 2 of the drawings.

The operation of my concrete block manufacturing machine is substantially as follows: The motor 99, as hereinbefore described, operates continuously for driving the pallet take-out rollers 89 and 90. The vibrator motor 18 operates continually rotating the vibrator shaft 13 by means of the pulleys 15 and 16 and the belt 17. The eccentrics 14 cause vibration of the shaft 13, which is transferred through the bearings 19a and 20a in connection with the brackets 19 and 20, which are rigidly secured to the hopper 2. Thus, the entire hopper 2 is subject to reactional forces imposed upon the links 11 and 12 in

engagement with the vibrating diaphragms 5 and 6 on the shafts 9a and 10a. It will therefore be understood that the entire hopper 2 is vibrated, in addition to the vibrational concentration within the areas at the downwardly converging sides thereof, occupied by the resilient diaphragms 5 and 6, which continually agitate the cementitious material in the hopper 2 as it passes downwardly into the preforming mold 2a beneath the lower edges of the material flow regulators 100 and 101, which may be vertically adjusted by means of the setscrews 102 and 103 in connection with each opposite end of each of the material regulators, for accommodating aggregate and other elements of the mixture, which may be varied as desired. The shelves 2b at the upper portion of the preforming mold 2a form a vertical abutment for the compacted material, preventing wedging action of the same against the ram 3 during its reciprocal movement about the core 4 as it passes upwardly and downwardly within the casing 2e which shields the ram 3 from material when dumped into the hopper 2.

The cam shaft 38 is rotated in a counter-clockwise direction, as shown in Fig. 2 of the drawings, and in a clockwise direction, as shown in Figs. 4, 5, 6 and 7 of the drawings, all as indicated by arrows on each view of said cam shaft 38. As shown in Fig. 2 of the drawings, the ram elevating cams 36 and 37, have rotated into position wherein the roller followers on the levers 32 and 33 have dropped over the precipice of each of the cams, permitting the ram 3 to fall by force of gravity, driving a column of the compacted material, from the preforming mold 2a of the hopper 2, downwardly into the mold box 21. It will be here noted that the forming mold bottom plate 23a, in connection with the mold block ejector 23, is held in flush relationship with the upper side of the screed plate portion 21g of the mold box 21, preliminary to the gravitational fall of the ram 3. The clips 81, shown in Fig. 10 of the drawings, operate as releasable detents and engage the frame 23c for supporting the plate 23a flush with the upper surface 21g of the screed plate portion of the mold box 21 until the ram 3 strikes the material in the preforming mold 2a. Thus, no air can be trapped in the cavity 21a of the mold 21, because the plate 23a is slideably positioned beneath the column of compacted concrete in the preforming mold 2a, and this flat plate 23a travels downwardly, in engagement with the bottom of the column of material when projected into the cavity 21a of the mold box 21, concurrent with the fall of the ram 3. The plate 23a remains in engagement with the bottom of the mass of material preventing dispersion thereof during its passage into abutted position at the bottom of the mold cavity 21a. It will be noted that when the ram 3 falls it slugs the upper portion of the compacted concrete column, and shears the same at the edge of the shelf 2b of the hopper 2. When the plate 23a is abutted on the top of the bars 23e and 23f, the column of material and the ram is thus abutted and stopped, a compressive shock wave travels throughout the column of material from the plate 23a to the ram 3, causing efficient compaction of the concrete material which has been preliminarily compacted and relieved of all compressible fluids by vibration, as hereinbefore described.

Immediately after the ram 3 has dropped, and compacted a block of material in the cavity 21a of the mold box 21, the transfer box 22 is raised by means of the cam 66, which acts on the cam follower roller 68 at its radially extended portion 66a, pivoting the lever 69, which places the links 71 and 72 in tension, which raises the transfer box 22 until it engages the flanges 24c on the plungers 24b, causing slight compression of the springs 24d thereby slightly elevating the plate 24a of the transfer box block ejector 24, above the level of the upper portion of the block which is resting on a pallet previously placed and supported in the pallet feed slide 65. It will be here noted that the transfer box 22 does not rise and strip the block held therein until the shock wave of the ram 3 has

passed, so that the formed block in the transfer box 22 is confined during such shock wave therein, preventing damage thereto, and actually contributing to the compaction of the formed block in the transfer box 22. Immediately after the transfer box 22 is raised and the block therein has been ejected therefrom, the slide plate 78 is actuated toward the pallet take-out rollers 89 and 90, forcing the pallet carrying the formed block intermediate the rollers 89 and 90, which deliver the same to a conveyor not shown in the drawing, and which is no part of my present invention.

This slide plate 78, actuated by the lever 77, link 76, lever 74 and cam follower 75, bearing on the cam 73, is retracted rapidly when the cam follower 75 traverses the radical slope 73a of said cam 73, as shown best in Fig. 7 of the drawings. Following the rapid retraction of the slide plate 78 by the spring 77c, the transfer box 22 again moves downwardly as the cam follower 63 passes the radical decline 66b of said cam 66, which permits the levers 69 and 70 to lower the transfer box 22, while the cam 60 actuates the forming mold 21 toward the transfer box, shearing the compacted column of concrete, completing the formation of a block which is carried into indexed position with the transfer mold 22, which concurrently indexes the pallet feed slide 65 with the pallet in the pallet chute 64. The cam track 69a is provided with a concentric dwell portion 69b, in which the cam follower 63 passes during the ejection of the formed concrete block from the cavity 21a of the mold box 21 into the transfer box cavity 22a. Ejection of the block from the cavity 21a of the mold box 21 into the cavity 22a of the transfer box 22 is accomplished by means of the cam 31 acting on the cam follower roller 30, which pivots the bell crank 27, causing elevation of the ejector elevator 25, which reciprocates the plate 23a in the mold box cavity 21a and positions the same in flush relation with the upper side of the screed plate 21g, at which location said plate 23a is held by the clips 81 hereinbefore described. The pallet slide 65 being connected to the mold box 21, moves in unison therewith. After the cam follower 63 has passed the dwell concentric portion 69b of the cam 69, the mold box 21 passes backwardly into indexed relationship with the preforming mold 2a, simultaneously moving the pallet slide 65, which breaks one pallet from the bottom of the stack in the pallet chute 64 and slidably places the same under the transfer box 22 in which the formed block has been positioned.

Preliminary to the drop of the ram 3, the toggle links 44 to 47, inclusive, are actuated and aligned vertically by the cam 51 engaging the roller 54 on the lever 53 connected to the link 52, which elevates the shoes 49 and 50, relieving the mold box supporting rollers 21b from the track 21c, so that the shock load is not borne by these rollers, which support the mold box 21 in its travels backwardly and forwardly along the frame 1 from the preforming mold 2a to the transfer mold 22. It will be noted that the cam 51 is provided with a short rise 51a, which permits the spring 55 to break the alignment of the toggle links 45 to 47, inclusive, shortly after the fall of the ram 3, which again places the rollers 21b on the track 21c ready to pass toward the transfer box 22, during the next cycle of operation, and the consecutive formation and delivery of each block.

It will be here noted that the rise 51a of the cam 51 covers a certain number of degrees of rotation of the cam shaft 38 sufficient to maintain the ejector elevator 25 in elevated position during the ejection of the formed block from the cavity 21a of the mold box 21 to the cavity 22a of the transfer box 22, and until the mold box 21 has almost returned to its fully indexed position with the preforming mold 2a.

In connection with the hereinbefore described concrete block manufacturing machine I practice a certain method of forming the concrete blocks, as follows: Material for forming concrete blocks, commonly known as "mud,"

which is a relatively dry cementitious mix of cement, aggregate and sand, together with a small amount of water, is first vibrated vigorously, until all of the compressible fluids are exhausted therefrom, or substantially all of the air has been relieved from the material. I then strike the upper portion of the compacted material, a single stroke, with a heavy ram, forcing the compacted material into a mold, and thereby completely filling the same, and then the material is abruptly stopped by abutment at the bottom of the mold, creating a compacting shock wave and solid compressive force within the material, which acts as a final and secondary compaction operation. Specifically, the method includes vibration and compaction of a mass of material into a preformed shape, wherein compressible fluids are substantially eliminated. Then the upper surface of the material is slugged, shearing the same at the profile of the preformed structure, and accelerating the same into a confined space coinciding with the preformed structure, while maintaining the foremost or bottom of the mass of material supported in a flat plane until abutted in the confined space, and then suddenly stopping the motion of the preformed structure, causing a radical compressive shock wave which acts as a secondary and final compaction operation. A block is then sheared laterally of the axis of the compaction shock wave from the preformed structure.

It will be here noted that the downwardly diverging draft relationship of the side walls of the preforming mold 2a provide vertical frictional relief of compacted material when slugged by the ram 3. This draft also prevents upward following of the compacted material when the ram is raised by the cams 36 and 37. It will be further noted that the vent 22g in the transfer box 22 relieves vacuum internally of a formed block when said transfer box 22 is raised.

Though I have shown and described a particular construction, combination and arrangement of parts and portions, and a certain method, I do not wish to be limited to this particular construction, combination and arrangement, nor to the particular method, but desire to include in the scope of my invention the construction, combination and arrangement, and a method substantially as set forth in the appended claims.

Having thus described my invention, what I claim as new and desire to secure by Letters Patent is:

1. In a block manufacturing machine, a preforming mold, means for charging said preforming mold with a mass of material, a forming mold positioned to receive a preformed mass from said preforming mold, a movable member in said forming mold adapted to engage one surface of a preformed mass of material in said preforming mold, an abutment in said forming mold, spaced from said preforming mold, providing a fixed stop for said movable member, and a ram adapted to force a preformed mass from said preforming mold and into said forming mold, thereby forcing said movable member and a preformed mass to move in said forming mold, whereby said movable member may remain in engagement with a preformed mass, until its movement is stopped by contact with said abutment.

2. In a block manufacturing machine, a preforming mold, means for charging said preforming mold with a mass of material, a forming mold positioned to receive a preformed mass from said preforming mold, a movable member in said forming mold adapted to engage one surface of a preformed mass of material in said preforming mold, an abutment in said forming mold, spaced from said preforming mold, providing a fixed stop for said movable member, a ram adapted to force a preformed mass from said preforming mold and into said forming mold, thereby forcing said movable member and a preformed mass to move in said forming mold, whereby said movable member may remain in engagement with a preformed mass, until its movement is stopped by contact with said abutment, and means mounting said forming mold for lateral

movement relative to said preforming mold adapted to shear a formed block in said forming mold from a mass of material in said preforming mold.

3. In a block manufacturing machine, a preforming mold, means for charging said preforming mold with a mass of material, a forming mold positioned to receive a preformed mass from said preforming mold, a movable member in said forming mold adapted to engage one surface of a preformed mass of material in said preforming mold, an abutment in said forming mold, spaced from said preforming mold, providing a fixed stop for said movable member, a ram adapted to force a preformed mass from said preforming mold and into said forming mold, thereby forcing said movable member and a preformed mass to move in said forming mold, whereby said movable member may remain in engagement with a preformed mass, until its movement is stopped by contact with said abutment, means mounting said forming mold for lateral movement relative to said preforming mold and adapted to shear a formed block in said forming mold from a mass of material in said preforming mold, and means for forcing said movable member away from said abutment for ejecting a block from said forming mold when it is laterally disposed relative to said preforming mold.
4. In a block manufacturing machine, a preforming mold, means for charging said preforming mold with a mass of material, a forming mold positioned to receive a preformed mass from said preforming mold, a movable member in said forming mold adapted to engage one surface of a preformed mass of material in said preforming mold, an abutment in said forming mold, spaced from said preforming mold, providing a fixed stop for said movable member, a ram adapted to force a preformed mass from said preforming mold and into said forming mold, thereby forcing said movable member and a preformed mass to move in said forming mold, whereby said movable member may remain in engagement with a preformed mass, until its movement is stopped by contact with said abutment, means mounting said forming mold for lateral movement relative to said preforming mold and adapted to shear a formed block in said forming mold from a mass of material in said preforming mold, and means for forcing said movable member away from said abutment for ejecting a block from said forming mold when it is laterally disposed relative to said preforming mold and means for positioning a pallet under a block ejected from said forming mold.

5. In a concrete block manufacturing machine, a frame, a hopper mounted on said frame, a preforming mold communicating with the lower portion of said hopper, a forming mold, having an upper end, positioned adjacent and below said preforming mold, a vertically movable bottom in said forming mold adapted to support the lower surface of a mass of material in said preforming mold, support means for holding said movable bottom in engagement with a mass in said preforming mold, an abutment in the lower portion of said forming mold providing a fixed stop for said movable bottom when forced downwardly, and a ram adapted to force the release of said support means from said movable bottom, and adapted to force a preformed mass, from said preforming mold and into said forming mold, thereby forcing said movable bottom downwardly, whereby said movable bottom may remain in engagement with a mass of material until the downward movement of said ram and a preformed mass is stopped by contact of said movable bottom with said abutment.

6. In a concrete block manufacturing machine, a frame, a hopper mounted on said frame, a preforming mold communicating with the lower portion of said hopper, a forming mold, having an upper open end, positioned adjacent and below said preforming mold, a vertically movable bottom in said forming mold adapted to support the lower surfaces of a mass of material in said preforming mold, support means for holding said movable bottom in engagement with a mass in said preformed mold,

an abutment in the lower portion of said forming mold providing a fixed stop for said movable bottom when forced downwardly, and a ram adapted to force the release of said support means from said movable bottom, and adapted to force a preformed mass, from said preforming mold and into said forming mold, thereby forcing said movable bottom downwardly, whereby said movable bottom may remain in engagement with a mass of material until the downward movement of said ram and a preformed mass is stopped by contact of said movable bottom with said abutment, said forming mold movable horizontally relative to said preforming mold and adapted to shear a block in said forming mold from the preformed mass in said preforming mold.

7. In a concrete block manufacturing machine, a frame, a hopper, mounted on said frame, a preforming mold communicating with the lower portion of said hopper, a forming mold, having an upper open end, positioned adjacent and below said preforming mold, a vertically movable bottom in said forming mold adapted to support the lower surface of a mass of material in said preforming mold, support means for holding said movable bottom in engagement with a mass in said preforming mold, an abutment in the lower portion of said forming mold providing a fixed stop for said movable bottom when forced downwardly, a ram adapted to force the release of said support means from said movable bottom and adapted to force a preformed mass, from said preforming mold, into said forming mold and thereby forcing said movable bottom downwardly, whereby said movable bottom may remain in engagement with said mass of material until the downward movement of a ram and said preformed mass is stopped by contact of said movable bottom with said abutment, said forming mold movable horizontally relative to said preforming mold for shearing a formed block in said forming mold from a preformed mass in said preforming mold and a transfer box having a lower open end disposed on a common plane with the upper open end of said forming mold, whereby horizontal movement of said forming mold permits it to be aligned with said transfer box, and means for moving said movable bottom upwardly in said forming mold adapted to force a block therefrom and into said transfer box.

8. In a concrete block manufacturing machine, a frame, a hopper mounted on said frame, a preforming mold communicating with the lower portion of said hopper, a forming mold, having an upper open end, positioned adjacent and below said preforming mold, a vertically movable bottom in said forming mold adapted to support the lower surface of a mass of material in said preforming mold, support means for holding said movable bottom in engagement with a mass in said preforming mold, an abutment in the lower portion of said forming mold providing a fixed stop for said movable bottom when forced downwardly, a ram adapted to force the release of said support means from said movable bottom, and adapted to force a preformed mass, from said preforming mold, into said forming mold and thereby forcing said movable bottom downwardly, whereby said movable bottom may remain in engagement with said mass of material until the downward movement of a ram and said preformed mass is stopped by contact of said movable bottom with said abutment, said forming mold movable horizontally relative to said preforming mold for shearing a formed block in said forming mold from a preformed mass in said preforming mold, a transfer box having a lower open end disposed on a common plane with the upper open end of said forming mold, whereby horizontal movement of said forming mold permits it to be aligned with said transfer box, means for moving said movable bottom upwardly in said forming mold adapted to force a block therefrom and into said transfer box and means for sliding a pallet under a block while in said transfer box.

9. In a concrete block manufacturing machine, a frame, a hopper mounted on said frame, a preforming

mold communicating with the lower portion of said hopper, a forming mold, having an upper open end, positioned adjacent and below said preforming mold, a vertically movable bottom in said forming mold adapted to support the lower surface of a mass of material in said preforming mold, support means for holding said movable bottom in engagement with a mass in said preforming mold, an abutment in the lower portion of said forming mold providing a fixed stop for said movable bottom when forced downwardly, a ram adapted to force the release of said support means from said movable bottom, and adapted to force a preformed mass, from said preforming mold, into said forming mold thereby forcing said movable bottom downwardly, whereby said movable bottom may remain in engagement with a mass of material until the downward movement of said ram and a preformed mass is stopped by contact of said movable bottom with said abutment, said forming mold movable horizontally relative to said preforming mold for shearing a block in said forming mold from a preformed mass in said preforming mold, a transfer box having a lower open end disposed on a common plane with the upper open end of said forming mold, whereby horizontal movement of said forming mold permits it to be aligned with said transfer box, means for moving said movable bottom upwardly in said forming mold for forcing a block therefrom and into said transfer box, means for sliding a pallet under a block while in said transfer box means for shifting said transfer box upwardly, and means for retaining said block stationary while said transfer box is moved upwardly to clear the upper surface of a block.

10. In a concrete block manufacturing machine, a frame, a hopper mounted on said frame, a preforming mold communicating with the lower portion of said hopper, a forming mold, having an upper open end, positioned adjacent and below said preforming mold, a vertically movable bottom in said forming mold adapted to support the lower surface of a mass of material in said preforming mold, support means for holding said movable bottom in engagement with a mass in said preforming mold, an abutment in the lower portion of said forming mold providing a fixed stop for said movable bottom when forced downwardly, a ram adapted to force the release of said support means from said movable bottom, and adapted to force a preformed mass, from said preforming mold, into said forming mold, thereby forcing said movable bottom downwardly, whereby said movable bottom may remain in engagement with a mass of material until the downward movement of said ram and a preformed mass is stopped by contact of said movable bottom with said abutment, said forming mold movable horizontally relative to said preforming mold for shearing a block in said forming mold from a preformed mass in said preforming mold, a transfer box having a lower open end disposed on a common plane with the upper open end of said forming mold, whereby horizontal movement of said forming mold permits it to be aligned with said transfer box, means for moving said movable bottom upwardly in said forming mold for forcing a block therefrom and into said transfer box, means for shifting said transfer box upwardly, and means for retaining said block stationary while said transfer box is moved upwardly to clear the upper surface of a block.

11. In a concrete block manufacturing machine, a frame, a material receiving hopper mounted on said frame, means for vibrating said hopper, a preforming mold communicating with the lower portion of said hopper, a forming mold having an upper open end positioned adjacent and below said preforming mold, a vertically movable bottom in said forming mold adapted to support the lower surface of a mass of material in said preforming

ing mold, support means for holding said movable bottom in engagement with said mass, an abutment in the lower portion of said forming mold providing a fixed stop for said movable bottom when forced downwardly, a ram adapted to force the release of said support means from said movable bottom, and adapted to force a preformed mass from said preforming mold and into said forming mold, thereby forcing said movable bottom downwardly, whereby said movable bottom may remain in engagement with a mass of material until the downward movement of said ram, and a preformed mass, is stopped by contact of said movable bottom with said abutment.

12. In a concrete block manufacturing machine, a frame, a hopper mounted on said frame, a preforming mold communicating with the lower portion of said hopper and adapted to preform a mass of material therein, a forming mold positioned adjacent and below said preforming mold, said preforming mold having an open lower outlet end, said forming mold having an upper open end adapted to receive a preformed mass from said preforming mold, a vertically movable bottom member in said forming mold and positioned to support the lower surface of a preformed mass of material at the outlet end of said preforming mold, detent means for releasably holding said bottom member so positioned, an abutment at the lower portion of said forming mold providing a fixed stop for said bottom member when forced downwardly and a ram adapted to slug a preformed mass disposed in said preforming mold for ramming a preformed mass downwardly into said forming mold, whereby said movable bottom member is released from said detent means and may remain in engagement with a preformed mass of material until the downward movement of said ram and a preformed mass is stopped by contact of said movable bottom member with said abutment.

13. In a concrete block manufacturing machine, a frame, a hopper mounted on said frame, means for vibrating said hopper, a preforming mold communicating with the lower portion of said hopper and adapted to preform a mass of material therein, a forming mold positioned adjacent and below said preforming mold, said preforming mold having an open lower outlet end, said forming mold having an upper open end adapted to receive a preformed mass from said preforming mold, a vertically movable bottom member in said forming mold and positioned to support the lower surface of a preformed mass of material at the outlet end of said preforming mold, detent means for releasably holding said bottom member so positioned, an abutment at the lower portion of said forming mold providing a fixed stop for said bottom member when forced downwardly, and a ram adapted to slug a preformed mass disposed in said preforming mold for ramming a preformed mass downwardly into said forming mold, whereby said movable bottom member may remain in engagement with a preformed mass of material until the downward movement of said ram and a preformed mass is stopped by contact of said movable bottom member with said abutment.

14. In a concrete block manufacturing machine, a preforming mold having an open outlet end and an opposed open end, means for charging said preforming mold with material, means for compacting material in said preforming mold, a ram near said opposite open end of said preforming mold for forcing material therethrough, a forming mold having an open end adapted to communicate with the open outlet end of said preforming mold, said ram adapted to ram a preformed mass of material from said preforming mold into said forming mold, means mounting said forming mold for movement laterally of said preforming mold and out of communication therewith to shear a block from a mass remaining in the preforming mold, and a screed plate movable relative to the open outlet end of said preforming mold and adapted to

close the same while said forming mold is out of communication with said preforming mold.

15. In a concrete block manufacturing machine of the class described, a hopper, a central casing in said hopper, a vertically reciprocal ram in said casing, a preforming mold at the outlet of said hopper, vibrating means in connection with said hopper, and a forming mold movably positioned beneath said preforming mold and adapted to coincide therewith, whereby concrete material is compacted by said vibrating means in said hopper above and into said preforming mold, and said ram is adapted to fall on the preformed material in said preforming mold for driving the same into said forming mold, causing compressive shock waves in said material as it abruptly abuts the bottom of said forming mold and reacts against said ram.

16. In a concrete block manufacturing machine, a preforming mold, means for charging the same with material, a forming mold horizontally movable below said preforming mold, a ram for forcing material from said preforming mold into said forming mold, said forming mold having rollers for supporting the same, track means for supporting said rollers, and means below said forming mold, adapted to raise the same, creating clearance between said rollers and said track means, for relieving shock on said rollers, when said ram forces material from said performing mold into said forming mold.

17. In a concrete block manufacturing machine, a frame, a forming mold horizontally movable on said frame, said forming mold open at its upper portion, a vertically movable transfer box open at its lower portion on a common plane with the upper portion of said forming mold, means for moving said forming mold into coincidence with said transfer box, a vertically movable bottom in said forming mold adapted to force a block upwardly into said transfer box, means for sliding a pallet under a block while it is in said transfer box, and means for vertically lifting said transfer box whereby the block is removed therefrom and remains on the pallet.

18. In a concrete block manufacturing machine, a frame, a forming mold horizontally movable on said frame, said forming mold open at its upper portion, a vertically movable transfer box open at its lower portion on a common plane with the upper portion of said forming mold, means for moving said forming mold into coincidence with said transfer box, a vertically movable bottom in said forming mold adapted to force a block upwardly into said transfer box, means for sliding a pallet under a block while it is in said transfer box, means for vertically lifting said transfer box, whereby the block is removed therefrom and remains on the pallet and a stripper plate for engaging the upper surface of the block in the transfer box when it is moved upwardly.

19. In a concrete block manufacturing machine, a frame, a forming mold horizontally movable on said frame, said forming mold open at its upper portion, a vertically movable transfer box open at its lower portion on a common plane with the upper portion of said forming mold, means for moving said forming mold into coincidence with said transfer box, a vertically movable bottom in said forming mold adapted to force a block upwardly into said transfer box, means for sliding a pallet under a block while it is in said transfer box, and means for vertically lifting said transfer box, whereby the block is removed therefrom and remains on the pallet, said forming mold and said transfer box having coinciding core structures therein and having corresponding cavities.

20. In a concrete block manufacturing machine, a frame, a material receiving hopper mounted on said frame, a vertical casing internally of said hopper, said casing enclosed at its upper portion, a ram vertically movable in said casing remote from material in said

hopper, and a preforming mold below said casing and spaced therefrom, whereby material flows into said preforming mold beneath said casing and said ram.

21. In a concrete block manufacturing machine, a frame, a material receiving hopper mounted on said frame, a vertical casing internally of said hopper, a ram vertically movable in said casing remote from material in said hopper, a preforming mold below said casing and spaced therefrom, whereby material flows into said preforming mold beneath said casing and said ram and a crosshead secured to said ram, and slots in said hopper communicating with the interior of said casing through which said crosshead extends.

22. In a concrete block manufacturing machine, a frame, a material receiving hopper mounted on said frame, a vertical casing internally of said hopper, a ram vertically movable in said casing remote from material in said hopper, a preforming mold below said casing and spaced therefrom, whereby material flows into said preforming mold beneath said casing and said ram, a crosshead secured to said ram, and slots in said hopper communicating with the interior of said casing through which said crosshead extends and weights on the extending ends of said crosshead disposed outwardly of said hopper.

23. In a concrete block manufacturing machine, a frame, a material receiving hopper mounted on said frame, a vertical casing internally of said hopper, a ram vertically movable in said casing remote from material in said hopper, a preforming mold below said casing and spaced therefrom, whereby material flows into said preforming mold beneath said casing and said ram, a crosshead secured to said ram, and slots in said hopper communicating with the interior of said casing through which said crosshead extends, weights on the extending ends of said crosshead disposed outwardly of said hopper and levers and precipice cam means for raising and dropping said crosshead together with said ram and said weights.

24. In a concrete block manufacturing machine, a preforming mold, a core structure internally of said preforming mold and coextensive therewith, a forming mold having a coextensive core structure therein, said forming mold having an open end adjacent said preforming mold adapted to receive a preformed block therefrom, both of said molds and their respective core structures adapted to coincide with each other, said core structure in said forming mold supported thereby distant from said open end, a movable member in said forming mold adapted to eject a block therefrom and a ram surrounding the core structure in said preforming mold and adapted to drive a preformed block therefrom and into said forming mold.

25. In a concrete block manufacturing machine, a frame, a material receiving hopper mounted on said frame, a vertical casing internally of said hopper, a ram vertically movable in said casing remote from material in said hopper, a mold below said casing and spaced therefrom, whereby material flows into said mold beneath said casing and said ram and vertically adjustable gates at the lower portions of said casing for adjustably restricting the passage of material flowing past the lower portions of said casing and into said mold, whereby the vertical depth of the material disposed beneath said ram, may be regulated.

26. In a concrete block manufacturing machine, a frame, a material receiving hopper mounted on said frame, a vertical casing internally of said hopper, a ram vertically movable in said casing remote from material in said hopper, a mold below said casing and spaced therefrom, whereby material flows into said mold beneath said casing and said ram and vertically adjustable gates at the lower portions of said casing for adjustably restricting the passage of material flowing past the lower portions of said casing and into said mold, whereby the vertical depth of the material disposed beneath said ram,

may be regulated, said ram when in its uppermost position is spaced above the lower portions of said gates.

27. In a concrete block manufacturing machine, a frame, a material receiving hopper mounted on said frame, a vertical casing internally of said hopper, a ram vertically movable in said casing remote from material in said hopper, a mold below said casing and spaced therefrom, whereby material flows into said mold beneath said casing and said ram and vertically adjustable gates at the lower portions of said casing for adjustably restricting the passage of material flowing past the lower portions of said casing and into said mold, whereby the vertical depth of the material, disposed beneath said ram, may be regulated, said ram, wherein its uppermost position is spaced above the lower portions of said gates, and means for vibrating said hopper.

28. A method of forming cementitious block, including preliminarily vibrating material, relieving compressible fluid therefrom, compacting a mass of material into a preforming mold, then slugging said mass of material

in said preforming mold and ramming the same downwardly into a forming mold against the bottom thereof, while maintaining the same form of said mass as preformed causing a compressive shock wave in said material upon initial slugging and a reactional shock wave

upon abrupt abutment of the material with the bottom of said forming mold, intermediate the same and the slugging medium.

29. A method of forming concrete blocks, including the vibration of a mass of cementitious material into a preforming mold, removing substantially all of the compressible fluids therefrom by said vibration, then slugging said mass of material in said preforming mold, driving the same therethrough into a forming mold, while main-

taining the same form of said mass, then suddenly stopping the movement of said material in said forming mold, creating a shock wave in said mass of material intermediate the bottom of said mold and the slugging me-

dium, and then shearing the formed material intermediate said preforming mold and said forming mold.

30. A method of forming cementitious block including preforming a mass of material, then slugging said mass of material and ramming the same into a confined space, while maintaining the same form of said mass as pre-

formed and abutting said mass in said confined space, causing a compressive shock wave of said material upon initial slugging and a reactional shock wave upon abrupt

abutment of the material within said confined space intermediate the same and the slugging medium.

31. A method of forming cementitious block, comprising, the preforming of a mass of damp cementitious material of greater displacement than a block to be formed, then slugging said preformed mass a single blow, thereby ramming a portion of the preformed mass into a

confined space while maintaining the same form of the mass as preformed, thereby completely filling the con-

fined space and then abruptly abutting said preformed mass in said confined space, whereby initial slugging of the preformed mass causes a compressive shock wave

therein, and abrupt abutment of said preformed mass in said confined space creates a reactional shock wave through the material of the preformed and confined mass, thereby absorbing full impact work of the slugging force,

in the mass of material, causing finished compaction of the cementitious block by said single blow.

32. A method of forming cementitious blocks, comprising, the preforming of a mass of damp cementitious material of greater displacement than a block to be

formed, then slugging said preformed mass a single blow, thereby ramming a portion of the preformed mass into a

confined space while maintaining the same form of the mass as preformed, thereby completely filling the con-

fined space and then abruptly abutting said preformed mass in said confined space, whereby initial slugging

of the preformed mass causes a compressive shock wave

therein, and abrupt abutment of said preformed mass in said confined space creates a reactional shock wave through the material of the preformed and confined mass, thereby absorbing full impact work of the slugging force, in the mass of material, causing finished compaction of the cementitious block by said single blow, then shearing the block in the confined space from the remaining preformed mass.
